UNITED STATES PATENT OFFICE.

JAMES M. TRINER, OF CHICAGO, ILLINOIS, ASSIGNOR TO THE PELOUSE SCALE AND MANUFACTURING COMPANY, OF SAME PLACE.

DESIGN FOR A SCALE-FRAME MEMBER.

SPECIFICATION forming part of Design No. 30,340, dated March 14, 1899.

Application filed February 18, 1899. Serial No. 705,730. Term of patent 14 years.

To all whom it may concern:

Be it known that I, JAMES M. TRINER, a citizen of the United States, residing at Chicago, in the county of Cook and State of Illinois, have invented and produced a certain new and original Design or Useful Shape for a Scale-Frame Member, of which the following, in connection with the accompanying drawings, is a full, clear, and exact specification.

In the said drawings, Figure 1 is a side elevation of a scale-frame member embodying my design. Fig. 2 is a rear elevation thereof; and Fig. 3 is a plan section taken on the line 3 3, Fig. 1.

The leading features of my design consist of a scale-frame member comprised by the two side walls A B and the back wall C.

When viewed from the top or in plan, as in Fig. 1, and also from the bottom, the walls A B C form a rectangular structure comprising two right angles adjacent to the wall C. The rear wall C extends from the extreme lower edges of the side walls A B, but terminates a short distance from their upper edges, and at the termination the corners of the side walls A B are rounded off, as shown at a b. The forward or opposite corners of the side walls A B are straight or substantially rec-

tangular for a short distance down their front edges, and they are then cut away, as shown at D, such cut-away portion having its edge running substantially parallel with the balance of the edge of the wall and terminating a considerable distance from the bottom.

The side wall A has a raised panel A', pressed outwardly therefrom with inwardly-rounding corners at its forward edge, an outwardly-rounding upper rear corner, and a rectangular lower rear corner, and the side wall B has a similar panel B'. The rear wall C is provided with an outwardly-pressed panel C', all of whose corners are inwardly rounded.

Each of the side walls A B at the rear side of their respective panels is provided with an outwardly-pressed perforated boss E at top and bottom.

Having thus described my invention, what I claim as new therein, and desire to secure by Letters Patent, is—

The design for a scale-frame member substantially as herein shown and described.

JAMES M. TRINER.
